UNITED STATES PATENT OFFICE

HARRY BRETTLER, OF BROOKLYN, NEW YORK, ASSIGNOR TO IDEAL LIGHTING NOVELTY CO., OF NEW YORK, N. Y., A PARTNERSHIP CONSISTING OF HARRY BRETTLER AND AARON HOLENDER

DESIGN FOR A LAMP OR ARTICLE OF ANALOGOUS NATURE

Application filed November 14, 1930. Serial No. 37,652. Term of patent 3½ years.

To all whom it may concern:

Be it known that I, HARRY BRETTLER, a citizen of the United States of America, and a resident of Brooklyn, county of Kings, and State of New York, have invented a new, original, and ornamental Design for Lamps or Articles of Analogous Nature, of which the following is a specification, reference being had to the accompanying drawing, forming a part hereof.

In the drawings:

Figure 1 is a front elevational view of the lamp or article of analogous nature; and

Figure 2 is a diagrammatic side elevational view of the same.

The coach A and horses B are of opaque openwork construction above the base, and the windows C of the coach are of translucent material.

I claim:

The ornamental design for a lamp or article of analogous nature substantially as shown and described.

HARRY BRETTLER.
